SLIPPER OR LIKE ARTICLE

Martin Kaye, New York, N. Y.

Application February 3, 1950, Serial No. 7,692

Term of patent 3½ years

(Cl. D7—7)

To all whom it may concern:

Be it known that I, Martin Kaye, a citizen of the United States of America, residing at Borough of Manhattan, in the county of New York and State of New York, have invented a new, original and ornamental, Design for Slipper or Like Article, of which the following is a specification, reference being had to the accompanying drawing, forming part thereof.

In the drawing:

Fig 1 is a side view of a slipper showing my new design;

Fig. 2 is a top view of said slipper; and

Fig. 3 is an enlarged sectional view taken substantially along the line of 3—3 of Fig. 1, and showing the manner in which the pile design stands out from the surface of the upper.

I claim:

The ornamental design for a slipper or like article, substantially as shown and described.

MARTIN KAYE.
